UNITED STATES PATENT OFFICE

2,611,371

GATE MECHANISM FOR CIGAR BUNCH
MACHINESSterling T. Gustavson, Brooklyn, N. Y., assignor
to International Cigar Machinery Company, a
corporation of New Jersey

Application February 15, 1947, Serial No. 728,904

5 Claims. (Cl. 131—21)

1

This invention relates to cigar making machines, more particularly to improvements in the filler feeds of scrap bunch cigar machines.

One of the main objects of the invention is to simplify the construction of the mechanism for operating the gate on the magazine containing a column of tobacco from which cigar bunch charges are separated after the column is compacted to a predetermined density. The scrap tobacco is automatically fed into the magazine when the gate is opened by the coaction of the gate with the scale pan in which a weighed quantity of tobacco is accumulated. Since a quantity of tobacco, which is slightly greater than that required for a cigar bunch charge, is thereby fed from the scale pan into the magazine when the gate is opened, the length of the column will gradually increase unless the opening of the gate is prevented. Therefore my improved gate operating mechanism is so controlled that the gate will not be opened when the length of the tobacco column becomes excessive.

My improved gate operating mechanism may include an actuating member pivotally connected to a cam lever and a pivoted member connected to the gate for opening the same. A suitable detent such as a tripping lever may be provided to maintain a pawl in a predetermined position out of contact with the actuating member until said lever is engaged by a tripping member connected to the plunger which compresses the tobacco column. If the tripping member should engage the tripping lever during the compression of the tobacco column by the plunger, the pawl will be released and will permit displacement of the actuating member transversely to a position wherein its movement up and down will operate said pivoted member and thereby open and close the gate. Since the actuating member is not disconnected from the pivoted member until the latter portion of its downward movement, the gate, although it falls into closed position, will create very little noise.

If the length of the tobacco column increases to such an extent that the plunger cannot move forwardly in the magazine sufficiently to permit the tripping member to engage the tripping lever, the pawl will not be released. Accordingly the actuating member will not be displaced transversely and the gate will not be opened until the length of the column is sufficiently decreased by the removal of bunch charges therefrom, to permit the tripping member to engage the tripping lever and thereby open the gate.

In the accompanying drawings which form a part of this specification:

2

Fig. 1 is a side elevation, partly in section, of a portion of a cigar bunch making machine equipped with a magazine gate mechanism embodying my invention;

5 Fig. 2 is an end elevation of the same, which is partly in section, as seen from line 2—2 of Fig. 1; and
Figs. 3 and 4 are side elevations of the control mechanism, illustrating the successive stages in 10 the operation of the same.

The filler feed for scrap bunch cigar machines, which is illustrated herein as equipped with my improved gate mechanism, is similar to the filler feed disclosed in the Durning Patent No. 15 2,306,381. The filler or scrap tobacco T is fed from a hopper 1 (Fig. 1), which is supported on metal leaf springs (not shown) and vibrated by suitable electro-magnetic devices such as shown in Patent 2,306,381, into a scale pan 3. The scale 20 pan 3 is similar in construction to the scale pan of Patent 2,306,381 and is provided with a wall 5 having lugs pivoted on scale arms supported on a scale shaft 6 supported in a bracket 7 and provided with a threaded stud 8 on which is 25 mounted a counterweight 9 which balances the scale pan and determines the amount of tobacco needed to trip it. The scale pan is also provided with a scale receptacle 10 which is pivoted on the upper end of wall 5. The tobacco drops from 30 hopper 1 through guide shield 11 into the pocket provided between the wall 5 and the scale receptacle 10 until sufficient tobacco accumulates to trip the scale pan.

When the scale pan is tripped, the vibration 35 of the hopper is stopped by mechanism described in Patent 2,306,381 and further discharge of tobacco from hopper 1 is prevented by a plate 12 which swings down upon the delivery end of the hopper 1 when the scale pan is tripped. During 40 each cycle of the machine a predetermined amount of filler tobacco is deposited into a magazine 14 in a manner hereinafter described when the scale pan is tripped. A predetermined quantity of tobacco sufficient for a bunch charge is 45 severed from the tobacco column A formed in magazine 14, by a reciprocating knife 16 and then rolled in a binder by a rolling apron 18 to form a cigar bunch.

The construction of magazine 14 is similar to 50 that described in Patent No. 2,306,381. It consists of a bottom plate 20, a pair of adjustable side plates 22 (Fig. 2), a stationary top plate 24 overlying the front end of plate 20, the oscillating gate 26 and a stationary top plate 28 overlying the rear end of plate 20. Top plates 24 and 55 28 are mounted on and supported by side rails 30

fastened to portions of bottom plate 20 outside of side plates 22.

The gate 26 is fastened on a shaft 118 supported in bearing brackets secured to rails 30. When gate 26 of the magazine 14 is closed in a manner hereinafter described, a reciprocating plunger 32 similar to that described in Patent 2,306,381 and slidable to and fro in the space between the plates 20 and 22 and gate 26 presses the tobacco column A into a charge transfer 34. The plunger 32 is equipped with a rod 35 slidably supported in a lug 36 threaded on a member 37 supported in an operating lug 38. The operating lug 38 is pivotally supported on the upper end of lever 44. To the outer end of said plunger rod 35 is fastened a laterally projecting trip bar 40 (Figs. 1, 2 and 3) carrying on its outer end an adjustable trip screw 42.

Operating lever 44 is connected by a link 46 to a cam lever 48 fulcrumed on a shaft 50 (Fig. 1) supported by housing 51. Cam lever 48 is provided with a cam follower 52 engaging a cam track in a cam 53 secured on a cam shaft 54 supported in suitable bearings of housing 51. Lever 44 is pivotally connected to links 55 and 56. Link 55 is pivoted on a stub shaft 57 supported in one side wall of housing 51. Link 56 is pivoted on a bracket 58 secured to a lug 59 formed on the inner face of the same side wall of housing 51. The cam track of cam 53 has the proper configuration to impart an oscillating motion to cam lever 48 and thereby move the lever 44 to operate the plunger 32.

As lever 44 moves forward the lug 36 presses against a compression spring 60 mounted on the plunger rod 35 and interposed between lug 36 and plunger 32 and thereby moves the plunger 32 forwardly. Spring 60 permits the arm 44 to complete its stroke regardless of variations in the length of the tobacco column A in the magazine 14. Thus a more or less uniform pressure will be exerted by plunger 32 upon the tobacco column during each forward stroke of lever 44. Since the trip bar 40 moves forwardly with plunger rod 35 and the trip screw 42 is supported on bar 40, the screw 42 will control the operation of my improved mechanism for operating the gate 26 of magazine 14.

The mechanism for operating the gate 26 includes a latch lever or latch 61 which is pivoted on stud 62 and is normally held by spring 64 in the position shown in Figs. 3 and 4. Spring 64 is anchored to a pin on housing 51 and is attached to a pin 66 on lever 61 so that the adjustable stop screw 68 on lever 61 rests against a stop 70 while an adjustable extension 60a of lever 61 holds the pawl or oscillating member 72 in the "set" position shown in Figs. 3 and 4. The pawl 72 is pivoted on a stud 73 threaded in housing 51.

If there is insufficient tobacco in magazine 14 the trip screw 42, when it is moved forwardly with plunger rod 35, will engage the lever 61 whereby the extension 60a will be disengaged from member 72 and the latter will thus be tripped. In one corner of member 72 is threaded an adjustable stop screw 76 (Fig. 2) which engages with a stop 78 fastened to housing 51 in order to limit the movement of member 72 upwardly in the direction of the arrow in Figure 3 under the influence of spring 80 attached to a pin 81 in the opposite end of member 72 after the latter is tripped. When oscillating member 72 is in the "set" position shown by Figs. 3 and 4, the spring 80 connected to pin 81 on member 72 serves to hold a wear or latch plate 82 attached to member 72

by screw 84 against the extension 60a of trip lever 61.

A link engaging device, such as a roller 86 is pivoted on a stud 88 secured in pawl 72, nut 60b is released, and extension 60a is manually adjusted to obtain the required "set" position of pawl 72 shown in Fig. 3 wherein roller 86 is out of contact with the side of a link 90 after which nut 60b is tightened. Link 90 is pivotally connected to a cam lever 108 which is provided with a cam follower 110 engaging a cam track of a cam 112 secured to shaft 54. In the upper end of link 90 is an L-shaped slot 92 in which roller 94 rides. Roller 94 is pivoted on a stud 96 secured in arm 98 and held in place by a washer 100 secured on stud 96. A tension spring 102 is attached to a pin 104 secured in lug 106 of link 90. Arm 98 is fixed to a shaft 114 supported in bearings in housing 51. If the arm 98 is turned it will actuate a lever 116 also fastened to shaft 114. A bell crank lever 120, which is fastened to the shaft 118 to which is also fastened the gate 26, is connected by a link 122 to lever 116. The link 122 is of conventional construction and its length may be manually adjusted to maintain the gate 26 at the proper position when closed. Thus motion from lever 116 will be transmitted to lever 120 for opening and closing the gate 26 in a manner hereinafter described, if the pawl 72 is tripped by trip screw 42.

In each cycle of the machine lever 44 moves forward and the plunger 32 compresses the tobacco A in the magazine 14 while the gate 26 is closed and the link 90 is at the dotted position shown in Fig. 3. If there is insufficient tobacco in column A the trip screw 42 will engage the lever 61 and move its end 60a off plate 82 of member 72 whereby spring 80 will pull pawl 72 into the tripped position shown in Fig. 1. When pawl 72 is tripped the roller 86, which engages the side of link 90 at the dotted position of the latter shown in Fig. 3, is moved out of contact with the side of link 90. This allows spring 102 to pull link 90 from the dotted position shown in Fig. 3 to the position shown in Fig. 1 wherein roller 94 engages abutment 91 forming an integral part of link 90 (Figure 4) of the transverse section 93 of L-slot 92 in link 90. Therefore the link 90 will open gate 26 when it is displaced upwardly by cam 108.

Link 90 then travels upwardly from the position shown in Fig. 1 to the position at which gate 26 is fully open (Fig. 3). During its upward movement lug 106 of link 90 comes in contact with relatching means, such as an adjustable stud 123 (Figs. 2, 3 and 4) threaded in a corner of the oscillating member 72 opposite stop screw 76. Lug 106 thus swings member 72 from the tripped position (Fig. 1) to the "set" position shown in Fig. 3 and spring 64 pulls lever 61 into position to maintain the member 72 in its "set" position shown in Fig. 3.

As link 90 is moved downwardly by cam lever 108 to swing the gate 26 from its open position B to its closed position C, the side of lever 90 comes into contact with roller 86 at the latter part of its downward stroke whereby link 90 is prevented from moving horizontally as arm 98 moves roller 94 in a downward arc. The lengths of the arms 98 and 108 have the proper proportions to cause the link 90 to engage the roller 86 at this portion of its downward stroke and be swung about its pivotal connection to cam lever 108. Consequently roller 94 moves forwardly out of the transverse portion of L-slot 92 to the top

of the longitudinal section 95 of the slot 92 as shown at the dotted position of link 98 in Fig. 3. When the magazine 14 requires an additional charge of tobacco and the scale pan 3 has been filled with the required weight of tobacco, the gate 26 swings upward in the direction indicated by the arrow in Fig. 1. As the gate 26 swings upward to its open position its free end engages a prong 128 on the scale receptacle 10 and causes the latter to swing away from wall 5 of the scale pan in the direction of the arrow in Fig. 1. The tobacco in the scale pan is thus permitted to discharge through a guide chute into the magazine 14. This guide chute comprises a pair of spaced stationary guide walls 126 and a swinging end wall 124, the gate 26 forming the other end wall of this guide chute. Wall 124 is secured to a flange 130 mounted on a shaft 132 supported in bracket 7. A lever 134 fastened on shaft 132 is connected by a link 136 to a lever 138 secured on shaft 118. Since the construction and operation of the guide chute is similar to that described in Patent 2,306,381, further description thereof is deemed unnecessary.

In order to prevent the scale pan from swinging upwardly as soon as its charge is dumped, the shaft 132 is provided with a lug 140 which during the upward motion of the gate 26 engages with a roller 142 on a lug 144 mounted on scale shaft 6. The scale pan is thus held from swinging upwardly while the gate 26 is in an upright position. This arrangement prevents the vibration of hopper 1 from resuming and feeding a new charge before the magazine gate 26 is closed and is fully described in Patent 2,306,381. As gate 26 disengages prong 128 during its downward motion, the scale receptacle 10 will, due to its own weight, swing back and contact wall 5 again, and the scale pan is ready to receive a new charge of tobacco.

The amount of tobacco A in magazine 14 steadily increases due to an excess of tobacco in each charge dumped by the scale pan until the forward motion of reciprocating plunger 32 is restricted to the point where tripping stud 42 does not move forwardly far enough to trip lever 61. Consequently extension 60a of lever 61 remains in contact with the wear plate 82 on the oscillating member 72 and retains member 72 in its "set" position C, Fig. 3. In this cycle, when cam lever 108 moves link 90 upwardly, the roller 94 remains in the longitudinal section 95 of the slot 92 while link 90 moves upwardly from the dotted position (Fig. 3) to the position shown in Fig. 4. Therefore no motion is imparted to arm 98, and as a result gate 26 remains closed and no further addition of tobacco to magazine 14 is made. Each time the tobacco charge is removed from the magazine the plunger moves farther forward until such a time as stud 42 again trips lever 60 and thereby permits the gate to be opened and admit more tobacco into the magazine.

What is claimed is:

1. In a cigar machine, the combination with a magazine containing a column of tobacco, of a gate pivotally mounted on said magazine and forming a part of one wall thereof when closed, a reciprocable plunger within said magazine adapted to compress the tobacco therein, means for moving said plunger forwardly in said magazine to compress the tobacco column therein, an actuator connected to said gate and adapted to open said gate to permit tobacco to be delivered to said magazine, a roller connected to said actuator,

ator, a link having an L-shaped slot engaging said roller, said slot having a transverse portion extending transversely of said link and a longitudinal portion extending longitudinally of said link, an oscillating member, a latch lever, a latch plate on said oscillating member, a device on said oscillating member operative when said latch lever engages said latch plate to maintain said device in engagement with said link and restrict the movement of said roller to said longitudinal portion of said slot, means operated by said plunger operating means for moving said latch lever to unlatching position relative to said latch plate and effect the movement of said device on said oscillating member away from said link, means operative substantially simultaneously with the movement of said device out of engagement with said link to displace said link transversely to position said roller in said transverse portion of said slot, and mechanism for moving said link longitudinally whereby said actuator will be operated and said gate will be opened when said roller engages the transverse portion of said slot.

2. In a cigar machine, the combination with a magazine containing a column of tobacco, of a gate pivotally mounted on said magazine and forming a part of one wall thereof when closed, an actuator connected to said gate and adapted to open said gate to permit tobacco to be delivered to said magazine, a roller connected to said actuator, a link having an L-shaped slot engaging said roller, said slot including a transverse portion extending transversely of said link and a longitudinal portion extending longitudinally of said link, a device for moving said link transversely to permit said roller to engage and be located in said transverse portion of said slot, and mechanism for moving said link longitudinally whereby said actuator will be operated and said gate will be opened when said roller engages the transverse portion of said slot.

3. In a cigar machine, the combination with a magazine containing a column of tobacco, of a gate pivotally mounted on said magazine and forming a part of one wall thereof when closed, means for compressing the tobacco in said magazine, an actuator connected to said gate and adapted when displaced to open said gate to permit tobacco to be delivered to said magazine, a link having an L-shaped slot, the base of the L forming an integral part thereof and abutment on said link adapted to engage and displace said actuator to open said gate to permit tobacco to be delivered to said magazine, mechanism normally maintaining said abutment of said link out of engagement with said actuator, including a device operated by said tobacco-compressing means when tobacco is to be delivered to said magazine for moving said link transversely to engage said abutment with said actuator, and mechanism operative after said abutment is in engagement with said actuator for moving said link longitudinally whereby said actuator will be displaced and said gate will be opened for delivery of a quantity of tobacco into said magazine.

4. In a cigar machine, the combination with a magazine containing a column of tobacco, of a gate pivotally mounted on said magazine and forming a part of one wall thereof when closed, a reciprocable plunger within said magazine adapted to compress the tobacco therein, means for moving said plunger forwardly in said magazine to compress the tobacco column therein, an actuator connected to said gate and adapted to

open said gate to permit tobacco to be delivered to said magazine, a roller connected to said actuator, a link having an L-shaped slot engaging said roller, said slot having a transverse portion extending transversely of said link and a longitudinal portion extending longitudinally of said link, mechanism normally restricting the movement of said roller to said longitudinal portion of said slot, said mechanism including a device engaging said link, an oscillating member supporting said device, and a latch engaging said member to maintain said device in engagement with said link, means operated by said plunger operating means for displacing said latch relative to said member, means for moving said unlatched member to position said device out of engagement with said link, means operative substantially simultaneously with the unlatching of said member for moving said link transversely to position said roller in said transverse portion of said slot, mechanism for moving said link longitudinally whereby said actuator will be operated and said gate will be opened when said roller engages the transverse portion of said slot, and relatching means carried by said link operative after the delivery of a predetermined quantity of tobacco to said magazine for relatching said latch and member thereby effecting the displacement of said roller out of said transverse slot portion and relocating it for movement in said longitudinal slot portion.

5. In a cigar machine, the combination with a magazine containing a column of tobacco, of a normally closed gate on said magazine adapted

to be moved to open position to permit tobacco to be delivered into said magazine, a plunger adapted to compress said tobacco column in said magazine, means for operating said plunger to compress said tobacco column, a pivoted member connected to said gate to move said gate to said open position, a cam lever, an actuating member pivotally mounted on said cam lever, said actuating member having an L-shaped slot, the base 10 of the L forming an integral part thereof and adapted to engage and operate said pivoted member when said actuating member is displaced transversely about its pivotal connection on said cam lever, a cam for operating said actuating member to displace said actuating member longitudinally after said transverse displacement, and mechanism operated by said plunger operating means for displacing said actuating member transversely about its pivotal connection on said cam lever and thereby positioning said abutment 15 of said actuating member in operative engagement with said pivoted member whereby said gate will be opened to permit tobacco to be delivered to said magazine.
